UNITED STATES PATENT OFFICE

WILLIAM A. DOWNING AND JAMES T. McHUGH, OF PITTSBURG, PENNSYLVANIA.

COIN AND DISK COUNTING MACHINE.

No. 861,817.

Specification of Letters Patent.

Patented July 30, 1907.

Application filed June 7, 1906. Serial No. 320,605.

To all whom it may concern:

Be it known that we, WILLIAM A. DOWNING and JAMES T. McHUGH, citizens of the United States of America, residing at Pittsburg, in the county of Allegheny and State of Pennsylvania, have invented certain new and useful Improvements in Coin and Disk Counting Machines, of which the following is a specification, reference being had therein to the accompanying drawing.

10 This invention relates to certain new and useful improvements in coin and disk counting machines, and the invention has for its object the provision of positive and reliable means for assembling loose coins or disks, temporarily holding the same, and then releasing them in predetermined quantities; the mechanism or machine employed for this purpose being extremely simple, durable and effective as a labor-saving device.

Our machine is particularly adapted for amusement 20 parks, arcades, banks and resorts, where small coins or their equivalent are handled in large quantities, and where considerable time is lost in counting and making change. Our invention aims to obviate the counting of coins or disks, and to provide a machine 25 which will accurately deliver a predetermined number of coins or disks at a time.

The invention further resides in the novel construction, combination and arrangement of parts to be presently described in detail and specifically pointed out 30 in the appended claims.

Reference will now be had to the drawings forming part of this specification, wherein similar numerals of reference designate corresponding parts in the several views, in which:-

35 Figure 1, is a plan of one of our improved coin or disk counting devices, Fig. 2, is a vertical longitudinal sectional view enlarged of same, Fig. 3, is a detail sectional view enlarged of a coin or disk-detaching plunger, Fig. 4, is a fragmentary perspective view of a casing 40 with two of the improved devices arranged therein, Fig. 5, is a front elevation of a casing having a plurality of the improved devices arranged therein, upon a smaller scale, Fig. 6, is a perspective view of one of the improved devices enlarged, showing the plunger in 45 the same position as in Fig. 2, Fig. 7, is a similar view of a device, illustrating the carrying-plunger partially moved, Fig. 8, is a plan of a counting-device containing disks, and Fig. 9, is a cross sectional view enlarged of one of the devices, with the plunger removed there- 50 from.

To put our invention into practice, we preferably arranged our machines in a casing 1 supported in an elevated position by legs 2 or similar supports. Upon the bottom 2^a of the casing is arranged a plurality of

the improved coin or disk counting devices, each of 55 which is independently operated to deliver a prescribed number of coins or disks.

Each device consists of an oblong frame 3 in which is slidably mounted a coin or disk-carrying plunger comprising a plate 4 having a central opening 5, the 60 upper edges of which are beveled, as at 6. The one end of the plate 4 is provided with a rod 7, which protrudes through the frame 3, as at 8, and through the front wall 9 of the casing 1. The outer end of the rod 7 is provided with a button or plate 10, upon which 65 is placed a numeral to designate the number of coins or disks delivered by the device. The opposite end of the plate 4 is provided with a rearwardly extending pin 11, while to the rear end of the frame 3 is fixed a tube 12 adapted to telescope said pin. Between and 70 surrounding said pin and tube is a coiled spring 14 adapted to normally hold the plate 4 at the forward end of the frame 3.

Mounted upon the frame 3 at the rear end of the plate 4 is a tube carrying plate 15, the vertical disposed 75 tube 16 of said plate lying directly above the opening 5 of the plate 4. The upper end of the tube 16 is beveled as at 17, and this tube is adapted to contain the coins or disks to be counted.

In the casing 1 is mounted an inclined plate 18 which 80 extends into close proximity to the beveled ends of the tubes 16. The plate 18 is recessed, as at 19, to convey coins or disks to said tubes, and the casing is provided with a hinged lid 20, with recesses 21 in said lid, when in an open position, alining with the recesses of the 85 plate 18, whereby a handful of coins or disks thrown upon said lid and plate will be guided into the tubes 16.

To insure a free and easy movement of the coin or disk carrying plungers, we provide the side rails 22 of the frames 3 with tongues 23 adapted to engage in 90 grooves 24 of the plates 4 of said plungers.

In order that prescribed quantities of coins or disks may be dispensed by the machine, we provide the bottom 2^a of the casing 1 with an opening 25, beneath each frame and to the rear of the plates 4, whereby the 95 openings 5 of said plates can be moved to register with the openings 25 of the casing.

The plungers of the devices vary in thickness according to the number of coins or disks to be delivered, the plunger of the first device simply holding one coin 100 or disk, which is dispensed by the machine when said plunger is pushed inwardly, transferring the coin or disk from beneath one of the tubes 16 to one of the openings 25 of the machine. The cashier or person using the machine places their hand beneath the machine to 105 catch the coin or coins dispensed thereby.

After a coin or disk carrying-plunger has been actuated to deliver one or more coins or disks, the coins or

disks remaining in the tube above said plunger are held by the forward imperforate end of the plate 4 of said plunger, and immediately upon the plunger being returned to its normal position by the spring 14, the 5 coins or disks descend into the opening 5 of said plunger stored in the tube 16 and those confined within said opening are ready to be moved forward to one of the openings 25 of the machine.

Referring now to Figs. 4 and 5 of the drawing, it 10 will be observed that we have provided the casing with eleven plungers, this number being preferable on account of obtaining a large number of combinations with a minimum number of coin or disk-carrying plungers. The counting devices have been consecutively arranged to deliver from one to ten coins or disks, and one device to deliver twenty, whereby by using 15 one or more plungers or some of the plungers twice, any desired number of coins or disks can be easily obtained.

Having fully described our invention, what we claim 20 as new and desire to secure by Letters Patent, is:—

1. A coin and disk counting machine embodying an elevated casing, an inclined recessed plate arranged within said casing, a hinged lid carried by said casing and having recesses formed therein adapted to align with the recesses 25 of said plate when said lid is in open position, a plurality of coin or disk carrying plungers slidably mounted in said casing, a vertically disposed tube mounted above each plunger and adapted to receive coin or disks from the recesses of said lid and plate, said plungers consisting of 30 plates adapted to transfer coins or disks from said tubes to the exterior of said casing, means to normally hold said plates beneath said tubes, and means actuated from the exterior of the casing to move said plungers, substantially as described.

35 2. In a device of the class described, a casing including a bottom member having a plurality of spaced discharge

apertures, guides arranged in pairs at each side of said apertures, a coin tube disposed upon each pair of said guides, a plurality of plungers of graduated thickness movably disposed respectively within said guides and beneath said tubes, and each formed with an imperforate and a perforate portion, and means for operating said plungers to cause the perforated portions of the same to be alternately disposed beneath said tube and over the apertures in said casing bottom.

40 3. In a device of the class described, a casing including a bottom member having a plurality of spaced discharge apertures, a plurality of coin tubes corresponding to said apertures and spaced therefrom, a plurality of plungers corresponding to said tubes and apertures and of graduated thickness and disposed for motion beneath said tubes and within said apertures and each formed with a perforate and an imperforate portion, and means for operating said plungers to cause the perforated portions to be alternately disposed beneath said tubes and above the apertures in said 45 casing bottom.

4. In a device of the class described, a casing including a bottom having a discharge aperture, a frame including spaced sides forming guides disposed at opposite sides of said aperture, a coin tube having a lateral base bearing 50 upon said spaced side guides and spaced from said aperture, a plunger movably disposed between said guides and beneath said tube and above said aperture, said plunger having an imperforate and a perforate portion, a spring bearing between said plunger and frame and operating to 55 yieldably maintain the plunger with its perforated portion beneath said tube, and means for actuating said plungers to cause the perforated portion thereof to be disposed above the discharge apertures.

In testimony whereof we affix our signatures in the 60 presence of two witnesses.

WILLIAM A. DOWNING.
JAMES T. MCNUGIL.
